(57) **CLAIM**

The ornamental design for a sprayer housing, as shown and described.

DESCRIPTION

FIG. 1 is a perspective view of an illustrative sprayer housing; FIGS. 2-5 are front, left, right and top views, respectively, of the illustrative sprayer housing of FIG. 1; and,

FIG. 6 is a front elevation view of the sprayer housing of FIG. 1 with a cooperating sprayer tank unit shown in broken lines, with the controls of the sprayer housing and the controls of the sprayer tank unit elevated and at about the same height.

The portions illustrated in broken lines on the figures are for illustrative purposes only and form no part of the claimed design.
